F. L. GEORGE.

COMBINATION JACK SPRING AND TOUCH REGULATOR FOR UPRIGHT PIANO ACTIONS.

APPLICATION FILED SEPT. 9, 1919.

1,353,649.

Patented Sept. 21, 1920.

FIG. 1.

UNITED STATES PATENT OFFICE.

FRANK L. GEORGE, OF LOS ANGELES, CALIFORNIA.

COMBINATION JACK-SPRING AND TOUCH-REGULATOR FOR UPRIGHT-PIANO ACTIONS.

1,353,649.

Specification of Letters Patent. Patented Sept. 21, 1920.

Application filed September 9, 1919. Serial No. 322,733.

To all whom it may concern:

Be it known that I, FRANK L. GEORGE, a citizen of the United States, residing at Los Angeles, in the county of Los Angeles and State of California, have invented new and useful Improvements in Combination Jack-Springs and Touch-Regulators for Upright-Piano Actions, of which the following is a specification.

10 My invention relates to a combination jack spring and touch regulator for upright pianos.

A very pronounced defect in the upright action of today is the fact that when the 15 action is set up, adjusted and regulated there is no way of changing the weight of the touch or action and any experienced retail salesman will readily testify to the fact that thousands upon thousands of sales have been 20 lost because the action was too heavy or the action was too light and because there was no way of remedying this defect or objection.

As a matter of simon pure truth the last 25 resort of many salesmen is to tell the customer that the shop man or tuner can easily and quickly change the touch to any desired weight, when deep down in his heart the salesman knows this to be a misrepresentation. If he lands the customer he also lands 30 a bunch of future trouble.

The old coil jack spring soon becomes 35 weak when used and often breaks and will sometimes jump out of the socket in the jack extension in which it rides and frequently one coil laps over another and produces a squeak. My object is to overcome this and other objections.

Figure 1 is a fragmentary side elevation 40 of an upright piano action having a combination jack spring and automatic touch regulator embodying the principles of my invention, the supporting parts being shown in cross section and parts being broken away 45 to show the details.

Fig. 2 is a fragmentary side elevation showing how the coil jack spring may be used with my construction.

The intermediate action rail 1 is rigidly 50 mounted in the action bracket 2. An intermediate flange 3 is secured to the front side of the rail 1 by a screw 4 and extends upwardly above the rail 1. The upper lever 5 is substantially horizontal and is connected to the upper end of the flange 3 by a

pin 6. An abstract 7 is connected near its upper end to the forward end of the upper lever 5 by a pin 8. The abstract 7 has an offset upper end portion 9 above the pin 8 and a jack 10 is connected to the upper 60 end of the offset portion 9 by a pin 11. An opening 12 is formed through the jack 10 near its lower end and a spring 13 has a double turn coil 14 mounted in the opening 12 and secured in place by a pin 15. The 65 end 16 of the spring extends forwardly from the coil 14 and has an eye through which the individual adjusting screw 17 is inserted and the adjusting screw 17 is tapped downwardly into the heel 18 extending forwardly from the lower end of the jack 10. The spring 13 has a longer end 19 extending from the opposite end of the coil from the end 16 and the long end 19 has a portion 20 curved downwardly to form a seat. 70

The tension of the spring 13 on the jack 10 is regulated by adjusting the screw 17. The main regulating rod 21 extends through all the action brackets 2 and at one end of the rod a crank arm 22 extends upwardly 80 from the rod 21. A crank 23 is formed upon the outer end of the crank arm 22 and fits through a vertical slot 24. The vertical slot 24 is formed in an adjusting bracket 25 having a head 26. The main action rail 27 85 is rigidly mounted in the action bracket 2 and the regulating rail 28 is connected to the main action rail by arm 29. A bracket 30 is secured to the regulating rail 28 and a small bracket 31 is secured to the main action rail 27. The collective regulating screw 32 has a left hand screw thread 33 seated through the head 26 and the screw extends through the brackets 30 and 31, there being a shoulder 34 upon one end of the screw 95 against the bracket 30 and a lock nut 35 upon the other end of the screw against the bracket 31 to hold the screw from endwise movement. A handle 36 is fixed upon the forward end of the screw 32 so that by manipulating the handle 36 the main regulating rod 21 may be rotated forwardly and backwardly. 100

A pressure arm 37 extends from the main regulating rod 21 for each action and each pressure arm 37 has a bearing portion 38 at its outer end bent at right angles and resting upon the seat 20. The screws 17 are individually manipulated to produce a uniform touch upon the keys and then the han- 110

dle 36 is manipulated to increase or decrease the weight of the touch throughout the key board.

By manipulating the handle 36 to the right or clockwise the bearing 26 will be moved backwardly and the bearings 38 will press downwardly upon the springs 13 and increase the weight of the touch, and by operating the handle 36 reversely the head 26 10 will move forwardly and lighten the touch. This adjustment will provide a variation in key weight ranging from two to five ounces.

If desired the ordinary coil spring 39 may be inserted between the seat 40 on the abstract 7 and the heel 18 of the jack 10 as 15 shown in Fig. 2.

The details of the action are shown, described and claimed in my co-pending applications, Serial Numbers 322728 and 322729.

20 The pressure downwardly by the bearings 38 upon the outer rear ends of the springs 13 press downwardly upon the jacks 10 and this pressure is communicated to the keys through the abstract 7. The touch is regulated to uniformity by manipulating the individual adjusting screws 17 and the collective touch is made lighter or heavier by manipulating the handle 36.

Thus I have produced a combination jack 30 spring and touch regulator for upright pianos comprising a main regulating rod rotatably mounted through the action brackets, a crank arm extending from the main regulating rod at right angles, a collective regulating screw rotatably mounted 35 and held against endwise movement, a head screw-seated upon the screw, a connection between the head and the crank arm whereby manipulation of the collective regulating screw will rotate the main regulating rod forwardly or backwardly, individual pressure arms extending from the main regulating rod, springs pivotally connected to the jacks intermediate of their ends and having corresponding ends engaging the pressure arms, and individual adjusting screws 40 connecting the other ends of the springs to the jacks, so that by manipulating the individual adjusting screws the individual 45 touch of each key may be adjusted to uniformity, and so that by manipulating the collective regulating screw the collective touch may be made lighter or heavier.

Various changes may be made without 50 departing from the spirit of my invention as claimed.

I claim:

1. In a jack spring and touch regulator for upright piano actions in combination, 55 brackets adapted to carry piano actions, the actions comprising mechanism embodying jacks, a collective touch regulating rod rotatably mounted through the action brackets, an arm extending from the collective regulating rod, a collective touch regu-

lating screw rotatably mounted in an action bracket, a nut for the screw pivotally connected with the arm of the regulating rod, jack springs having eyes at one end, coils on the same plane as the eyes and adjacent thereto and a hook at the end opposite from the eyes, said springs being mounted upon the jacks with their eyes held by a vertically operated regulating screw and their coils held loosely by a horizontal pin, the hook end of the springs extending outwardly from the jacks, and arms upon the regulating rods having ends adapted to receive the hook ends of the springs whereby the manipulation of the collective regulating screw will operate to exert a greater or less spring pressure downwardly upon all the jacks in unison and whereby a vertical adjustment of the screws holding the eyes of the springs to the jacks will regulate the 80 spring pressure upon any individual jack.

2. In combination in a jack spring and touch regulator for upright piano actions, brackets adapted to carry piano actions, the actions comprising mechanism embodying 90 jacks, a collective touch regulating rod operatively mounted in the brackets, jack springs mounted upon the jacks and extending backwardly therefrom, means mounted upon the collective touch regulating rod for engaging 95 the free ends of the jack springs, and means for operating the touch regulating rod whereby the springs will be caused to exert a desired pressure downwardly upon the jacks.

3. In a jack spring and touch regulator for upright piano actions, in combination, brackets adapted to carry piano actions, the piano actions comprising mechanism embodying jacks, jack springs mounted upon the jacks by means adapted to be adjusted vertically whereby the spring pressure on any individual jack may be varied, and means for collectively varying the spring pressure exerted downwardly upon the jacks 110 by the jack springs.

4. In combination in a jack spring and touch regulator for upright piano actions, brackets adapted to carry piano actions, the piano actions comprising mechanism embodying jacks, a collective touch regulating rod operatively mounted in the brackets, means for rocking the regulating rod to a desired position of adjustment, arms mounted upon the rod, one for each of the actions, 115 springs connected to the jacks and extending outwardly and engaging the arms of the rod whereby the spring pressure downwardly upon the jacks may be collectively regulated, and means mounted upon the jacks for regulating the pressure of each individual spring downwardly.

5. In a jack spring and touch regulator for upright piano actions, in combination, a jack having a slot from front to rear adj-

cent to its lower end, a spring having an eye adapted to be held by a vertically adjustable screw on a portion of the jack forwardly of the slot and having a coil adapted to operate 5 within the slot, there being a pin through the jack across the slot and through the coil, and having a backwardly extending portion

adapted to be engaged by means for lowering the outer end thereof and means for lowering the outer ends of the spring to any 10 desired position.

In testimony whereof I have signed my name to this specification.

FRANK L. GEORGE.
